CENTRIFUGAL SYSTEM OF WET SPINNING
OF NATURAL FIBERS

Aldo Bolelli, Bologna, Italy

Application September 21, 1950, Serial No. 186,092

Claims priority, application Italy February 1, 1950

5 Claims. (Cl. 57—35)

1

This invention relates to an improved method for wet centrifugal spinning of natural fibers such as flax, hemp, ramie fibers and the like, and to an improved apparatus therefor.

It is an object of this invention to apply the centrifugal spinning to the natural fibers which have to be spun by a process, in such a manner as to avoid the rewinding of the annulus, formed in the centrifugal spinning on to a bobbin in order to allow extraction of the yarn spun from the rotary vessel, and to forward the same to the required successive working phases, and wherein the annulus obtained keeps its original form when undergoing drying.

It is another object of the invention to provide a method whereby, during the centrifugal spinning of the fibers, it is not necessary to effect rewinding after breakage of the yarn and to provide means for gathering the end of the yarn already spun within a vessel. In this method, in the event of a breakage, it is only necessary to piece the broken end which projects from the drawing rollers with a piece of yarn supplied by the operator, the other end of which is brought into the vessel, which is permitted to continue running. The operator is not concerned with the loose end of the broken yarn remaining in the mass already spun. Owing to the wetting of the sliver to be spun, the annulus of yarn formed in the rotary vessel remains stiff when the vessel is stopped.

An apparatus for carrying out the present invention is illustrated by way of example in the accompanying drawings in which:

Figure 1 diagrammatically illustrates the apparatus with the elements shown in their starting position;

Figure 2 diagrammatically illustrates the apparatus with the elements shown during the winding phase when the annulus is formed;

Figure 3 diagrammatically illustrates the apparatus with the elements shown in their position when the annulus is formed and the yarn holder is lifted for permitting the extraction of the annulus from the vessel;

Figure 4 diagrammatically illustrates the apparatus with the elements shown in their position when the yarn has been broken and the piecing up of the yarn is prepared;

Figure 5 diagrammatically illustrates the

2

phase of the extraction of the annulus from the vessel;

Figures 6, 7, 8, 9 and 10 illustrate different phases of separating the annulus;

Figure 11 illustrates a vertical section of the apparatus for carrying out the process; and

Figure 12 illustrates a lateral view of the apparatus.

Referring now to Figure 1, 12 indicates the roving which has previously undergone a wetting as required by the nature of the fibers to be spun, coming from the drawing rollers 1 and introduced in the yarn holder 3 supported by a lever 6, which is provided with a handle 13 and is pivoted on pivot 15 of bracket 7. The bracket 7 is provided with a pin 16 which abuts against surface 14 of lever 6. The bracket 7 bears on controlling rod 8 which is caused to vertically reciprocate by rotation of a heart-shaped cam 9. For the sake of simplicity in Figures 1, 2, 3 and 4, the cam 9 is shown as acting directly against the lower end of rod 8 whereas in Figure 11 there is illustrated in detail an arrangement of the cam 9 with respect to the rod 8.

The lifting and the lowering of lever 6 (Figure 2) due to the rotation of cam 9 causes a reciprocating vertical motion of the lever 6 and therefore of the yarn holder inside the vessel 2. The lever 6 may be hand operated through handle 13, which lifts the yarn holder from the vessel 2 by causing the same to rotate around pivot 15.

The vessel 2 is provided with a cover 4, centrally bored and provided with a border projecting downward into the vessel. In order to prevent the centrifugally spun yarn from sticking to the inner wall of the vessel 2, a resilient cylinder formed with a resilient membrane 5 folded on itself is inserted in the vessel, which owing to its elasticity is kept in contact with the inner wall of the border of the cover 4 so that by lifting the cover from the vessel, the membrane 5 is lifted therewith.

When the vessel is put in rapid rotation and the roving 12 is introduced in the vessel through the yarn holder 3, the centrifugal spinning starts and through the combined rotation of the vessel 2 and the reciprocating motion of the yarn holder 3 an annulus 19 is formed which presses against the inner surface of membrane 5.

When the annulus is completed, the yarn holder 3 is lifted by hand by means of the handle 13, and the yarn is cut (Figure 3) so as to allow removing the membrane 5 and the annulus therewith from the vessel.

In the event of a breakage of the yarn during the centrifugal spinning, the yarn holder 3 is lifted (Figure 4) and the operator introduces in the yarn holder a piece of yarn 12' having a length of about 50 cm.; then the yarn holder is again lowered into the vessel, which was kept in rotation, and the lower end of the yarn starts rotating, thus obtaining stretching and twisting of the yarn. At this time, the operator puts the other end of the yarn 12' in contact with the loose end of the broken roving projecting from the drawing rollers, thus effecting the piecing together of the piece 12' with the roving 12. It is not necessary for the operator to take any action as regards the loose end remaining in the mass of yarn already spun at the moment of the breakage.

When the annulus is completed, the apparatus is stopped, the yarn holder 3 is lifted by hand by means of the handle 13 and the yarn is cut (Figure 3) so as to allow removing the membrane 5 and the annulus therewith from the vessel. The removal takes place by lifting the cover 4 which takes with it the membrane 5. In order to free the membrane and the annulus from the cover, use is made of the pincers 11 (Figures 6 and 7), formed by two semicircular arms pivoted to each other at one end, and provided, at the other end, with handles. The arms of the pincers are separated sufficiently to allow surrounding the periphery of the membrane 5 and a slight pressure is then exerted, until the cover 4 may be easily removed. At the same time, a second resilient cylinder 10 constructed from an elastic membrane folded on itself is introduced in the central hole of the annulus and made to contact, owing to its elasticity, with the inner surface of the annulus. Thus, the form of the annulus is kept unaltered during the successive phase of the working cycle. When the membrane 10 is introduced, the pincers 11 are loosened so as to allow the membrane 5 to open and to be removed.

As may be seen from Figure 11, the roving 12 coming from the creel 20 passes through a tank 25 containing heated water and goes to the delivery rollers 21 which supply the same to the drawing rollers 1 from which the roving extends through the yarn holder 3 to the rotating vessel 2. Near the vessel there is located a basin 22 for collecting any liquid set free during the centrifugal spinning.

The vessel 2 is rotated by shaft 23 operated through belt 18 by wheel 17. For obtaining the vertical reciprocating motion of the yarn holder 3, a lever 26 pivoted at 27 is provided which is in touch (Fig. 12), through roller 29 with the heart-shaped cam 9 which may rotate round the shaft 30 in any usual manner, not shown in the drawing. On the lower portion of lever 26 a flexible connection member 32 is fixed, which winds around the periphery of wheel 33, provided with a hub 34 (Fig. 11) which is rotatable around shaft 24. A chain 31 (Fig. 11) fixed to the hub 34 is connected at the other end to the lower end of rod 8, which supports the bracket 7. The chain 31 may be wound on the hub for a sufficient amount to provide the desired oscillation of lever 26.

I claim:

1. A method for wet centrifugal spinning of

flax, hemp, ramie fibers and the like comprising winding up a wet roving which is passed through drawing rollers, inside a rapidly rotating vessel having an axially bored cover provided with a peripheral border projecting downward, against which border presses a resilient hollow cylinder made with an elastic membrane folded on itself, forming in said cylinder an annulus of yarn in contact with the membrane, removing said annulus and said cylinder from the vessel by lifting the cover and together therewith said elastic cylinder pressing the periphery of said cylinder, removing said cylinder from the cover, introducing into the inner cavity of the annulus a second hollow resilient cylinder made with an elastic membrane folded on itself in contact with the inner surface of the annulus, whereby the said annulus is ready to be directly dried, without first effecting re-winding of the yarn of the annulus formed onto a bobbin.

2. A method as claimed in claim 1, wherein piecing together of yarn which has broken during centrifugal spinning is obtained by introducing a portion of yarn in the yarn holder, which portion of yarn at one end is brought into contact with the inner surface of the annulus already formed when the breakage occurred, which is kept in rotation and at the other end contacted with the broken end of the roving projecting from the drawing rollers and connected to said roving through the twisting undergone by the portion of yarn due to the rotation of the annulus.

3. An apparatus for wet centrifugal spinning of flax, hemp, ramie fibers and the like comprising in combination a tank adapted for containing hot water for wetting the roving, a pair of drawing rollers positioned near the outlet end of said tank, means for supplying the roving to said rollers, a rapidly rotatable vessel located beneath said drawing rollers having an axially bored cover provided with a peripheral downward projecting border, a resilient cylinder formed of an elastic membrane folded on itself inserted in said vessel, pressing against the inner surface of the border of the cover and supported therefrom, a yarn holder for guiding the roving coming from the drawing rollers inside the rotating vessel to be centrifugally spun in such a manner as to be held against the inner surface of said resilient cylinder to form an annulus of yarn, said elastic cylinder being removable from the cover of the vessel after the cover has been lifted.

4. An apparatus for wet centrifugal spinning of flax, hemp, ramie fibers and like, comprising in combination a roving wetting tank, a pair of drawing rollers and means for supplying the roving thereto from said tank, a rapidly rotatable vessel located beneath said drawing rollers, an axially bored cover for said vessel having a peripheral downward projecting border thereon, a resilient cylinder formed by an elastic membrane folded on itself inserted in said vessel and pressing against the inner surface of the border of the cover and being supported therefrom, a yarn holder for guiding the roving from the drawing rollers into the inside of said rotating vessel to be centrifugally spun therein and held against the inner surface of said resilient cylinder to form an annulus of yarn, means for imparting to the yarn holder a vertical reciprocating motion during the spinning operation, and means for lifting said yarn holder for removing the same from the said vessel.

5. An apparatus is claimed in claim 4, wherein

said means for imparting to the yarn holder a vertical reciprocating motion comprises a heart-shaped cam, a pivotally mounted oscillatable lever pressing against said cam and being reciprocable thereby, a rotatably mounted wheel having a hub, a flexible connection between said oscillatable lever and said wheel for angular movement of said wheel, a controlling rod attached to the yarn holder, a chain connected at one end to said rod and at the other end to said hub of said wheel, angular motion of said wheel being transformed into reciprocating motion of said controlling rod and said yarn holder by said chain.

ALDO BOLELLI. 15
